UNITED STATES PATENT OFFICE.

CURTIS D. McCLELLAN AND JOHN FLYNN, OF WASHINGTON, IOWA.

FIGURED TOY.

1,337,932.

Specification of Letters Patent. Patented Apr. 20, 1920.

Application filed June 25, 1919. Serial No. 306,686.

To all whom it may concern:

Be it known that we, CURTIS D. McCLELLAN and JOHN FLYNN, citizens of the United States, residing at Washington, in the county of Washington and State of Iowa, have invented certain new and useful Improvements in Figured Toys; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in figured toys and consists essentially in the provision of a gallows and means for automatically causing the figure to be suspended by a rope in the act of hanging, and in the provision of means for resetting the device.

Our invention consists of a simple device of this character having various details of construction, combination and arrangement of parts which will be hereinafter fully described, shown in the accompanying drawings and then specifically defined in the appended claims.

Our invention is illustrated in the accompanying drawings which, with the letters of reference marked thereon, form a part of this application and in which:

Figure 1 is an elevation.

Fig. 2 is a side view and

Fig. 3 is an enlarged detail view of the trap resetting device.

Reference now being had to the details of the drawings by letter:

A designates a board representing a target with a bull's eye opening B, and C is a gallows having a lateral extension D at its upper end, and E are pulleys journaled upon the gallows and over which a rope F passes, and which also passes about a pulley H, and thence extends to and winds about a drum K journaled in suitable bearings in the rear of said board and the standard I. A weight L is fastened to said rope behind the board and said weight is adapted to cause a figure toy N, about the neck of which a slip noose is fastened, to be elevated as the weight falls. Fixed to the drum is a ratchet wheel Q, the drum being provided with a circumferential groove R adjacent to

the teeth of said gear. The bull's eye S is mounted directly back of the opening B in the board, and upon a bar T pivoted at T' and having a projection S' at one end, with a tooth for engagement with the teeth of the gear wheel Q. A cord T² is connected to said bar and affords means whereby the same may be drawn back to normal position after the bar has been tilted when the bull's eye is struck.

After the bar T is tilted by the impact of a ball or other object against the target, the tooth upon the projection S' will be thrown out of engagement with the teeth of the gear Q, and the weight secured to said rope will cause the latter to wind upon the drum and elevate the figure, about the neck of which the rope is connected.

When it is desired to reset the device, the rope may be rewound upon the drum by pulling upon a rope W, which is adapted to cause the drum to rewind and by pulling upon the cord T² the device may be set ready for operation.

What we claim to be new is:

1. A figured toy, comprising a frame, a board representing a target and having a bull's eye opening, a gallows rising adjacent to the board, pulleys thereon, a rope passing about said pulleys, a toy secured to said rope, a drum mounted in suitable bearings in said frame and about which said rope winds, a weight secured to the rope, a gear wheel fixed to the drum, a member mounted in the rear of said board, said member adapted to engage the teeth of the gear wheel, and means for releasing the same from the gear to permit the weight to fall and the toy to be raised and held suspended, and means for rewinding the rope to which the figure is fastened.

2. A figured toy, comprising a frame, a board representing a target and having a bull's eye opening, a gallows rising adjacent to the board, pulleys thereon, a rope passing about said pulleys, a toy secured to said rope, a drum mounted in suitable bearings in said frame and about which said rope winds, a weight secured to the rope, a gear wheel fixed to the drum, a member mounted in the rear of said board, said resilient member adapted to engage the teeth of the gear wheel, and means for releasing the same from the gear to permit the weight to fall and the toy to be raised.

and held suspended, said rope fastened to and adapted to wind about said drum and pulleys over which said second rope passes.

3. A figured toy, comprising a frame, a board representing a target and having a bull's eye opening, a gallows rising adjacent to the board, pulleys thereon, a rope passing about said pulleys, a toy secured to said rope, a drum mounted in suitable bearings in said frame and about which said rope winds, a weight secured to the rope, a gear wheel fixed to the drum, a bar pivoted at one end and a board at its other end serving as a bull's eye and adapted to be normally positioned back of the opening in said tar-

get, and provided with a downwardly extending projection designed to engage the teeth of the gear, said drum provided with an annular shoulder upon which the extension rides when released from the gear 20 teeth, and a rope attached to said member for releasing the same from the gear, and rope for rewinding the drum.

In testimony whereof we hereunto affix our signatures.

CURTIS D. McCLELLAN.
JOHN FLYNN.

Witnesses to signatures:

ALLEN J. FIELDS,
W. G. KNAUSS.
